FIG. 1

FIG. 2

FIG. 3

Albert Brauer
Inventor

By *Geo. H. Kimmel*

Attorney

UNITED STATES PATENT OFFICE.

ALBERT BRAUER, OF MILLINGTON, MICHIGAN.

EXTENSIBLE STOVEPIPE.

1,256,654.

Specification of Letters Patent. Patented Feb. 19, 1918.

Application filed December 12, 1917. Serial No. 206,805.

To all whom it may concern:

Be it known that I, ALBERT BRAUER, a citizen of the United States, residing at Millington, in the county of Tuscola and State 5 of Michigan, have invented certain new and useful Improvements in Extensible Stovepipes, of which the following is a specification.

This invention relates to furnace and 10 stove attachments and it is the principal object of the invention to provide an improved extensible pipe capable of being adjusted to the desired length in order that the measuring and cutting of the same to correspond to the distance between a flue or chimney and the draft opening of a furnace or 15 stove will be eliminated.

Another and equally important object of 20 the invention is to provide the stove pipe with novel means for securing the same in adjusted position, thus, preventing undue movement thereof and the resultant escape of soot and other dirt therefrom.

Other objects will be in part obvious and 25 in part pointed out hereinafter.

The improvements in the details and arrangement of parts will be apparent from 30 an inspection of the accompanying drawings, in connection with the specific description hereinafter contained, and wherein the preferred embodiment of the invention is shown and described for the purpose of facilitating a full understanding of the same.

35 In the drawings:—

Figure 1 is a longitudinal section through an adjustable stove pipe having the improved attachment engaged therewith,

Fig. 2 is a fragmentary elevation of the 40 same showing parts in section.

Fig. 3 is a detail in perspective of the stop.

Having more particular reference to the drawings, in connection with which like 45 reference characters will designate corresponding parts, 1 and 2 represent the telescopically engaged tubular sections of the conventional stove pipe, which sections, as will be understood, have certain of the ends 50 thereof constricted in order that they may be effectually engaged with each other.

Extending longitudinally of the inner section 1 and secured to the same by rivets

or like fastening devices 3 is a strip of metal 4 provided with an elongated longitudinally 55 disposed groove, the groove, obviously, extending for approximately the entire length of the strip.

A plate 6 is slidably arranged on the strip 4 and is apertured to permit the passing of a bolt 7 therethrough and through the longitudinally disposed slot formed therein. A washer 8 or like bearing element is arranged over the bolt 7 and upon the strip 4 while a locking nut 9 is turned into engagement 65 with the screw threaded end of said bolt and obviously, serves to clamp the plate 6 to said strip. As will be noted, one end of the plate is bent upwardly to provide an engaging lip 10, which lip is adapted to be engaged, at times, with the adjacent end portion of the outer stove pipe section 1.

In using my improved extensible stove pipe, the sections 1 and 2 are adjusted to the proper distance whereupon the plate 6 is 75 adjusted on the strip 4 to a point whereat the lip 10 of the same engages the adjacent marginal portion of the outer section. Thus, collapsing or telescoping of the sections will be positively prevented and as a 80 consequence, the same will be maintained in proper position when engaged with a flue or chimney and the draft opening of a furnace or stove. Obviously, other adjustments may be effected by merely loosening 85 and resetting the plate 6 and the engaging lip 10 formed thereon.

Manifestly, the construction shown is capable of considerable modification and such modification as is within the scope of my 90 claim, I consider within the spirit of my invention.

I claim:—

In combination with telescopically engaged pipe sections, a longitudinally disposed slotted member secured at one end to the inner section, a plate slidable on said member and having one end of the same bent upwardly to form means for engaging the adjacent end of the outer section, and securing means passing through said plate and the slot in said member.

In testimony whereof, I affix my signature hereto.

ALBERT BRAUER.
